COLLAPSIBLE SHIPPING CONTAINER

Clifford D. Fallert, St. Louis, Mo., assignor to Crown Zellerbach Corporation, San Francisco, Calif., a corporation of Nevada

Filed July 24, 1958, Ser. No. 750,687

1 Claim. (Cl. 229—41)

The invention relates broadly to improvements in shipping containers constructed of solid fibreboard, corrugate fibreboard or any other suitable bendable material and in particular to a container with top and bottom closure flaps that may be fully erected by the manufacturer and the bottom closure flaps securely sealed and then collapsed for shipment and storage.

A regular slotted carton, the most common fibreboard container construction, consists of opposed pairs of hingedly connected vertical walls and top and bottom flaps attached to the upper and lower margins of the vertical walls. The flaps are folded inwardly to a right angular lapped relationship, thereby forming top and bottom closures. This type container is normally shipped and stored in a flat condition and must be assembled by the user to a box-like condition and the bottom flaps sealed by a suitable means prior to placing articles in the container.

In many utilizations of this type container the necessity of forming the container and sealing the bottom flaps causes hardships and uneconomic operations such as in the field packing of lettuce. Lettuce cartons as an example are commonly erected in the harvest field by means of a truck mounted stitching machine that seals the bottom flaps and thereby eliminates the necessity of transporting the formed and bottom sealed cartons. The field assembly method requires considerable capital investment and the operator must work under rather difficult conditions.

An alternative method, requiring the carton manufacturer to apply pressure sensitive adhesive to the bottom flaps, eliminates some of the disadvantages of the field stitching operation but the nature of pressure sensitive adhesives is such that they are subject to deterioration prior to usage and following manual closure and sealing of the bottom flaps, the adhesive bond is subject to failure after prolonged stress.

Previous attempts, disclosed in the patent art, to provide cartons collapsible by the manufacture following assembly and of the general form of a regular slotted carton, will not permit the use of the more efficient one piece container blank or they are collapsible in a manner which injects one or more additional thicknesses of the container forming material between pairs of foldably connected panels and thereby prevent a flatwise contacting relationship of these panels in the collapsed condition. This results in excessive resistance to complete collapsing of the carton and in crushing of the container forming materials and undue stress on the outer plies at the folds.

There has been a continuing need for a regular slotted type carton that could be preassembled by the manufacturer and then collapsed for convenient storage and transportation. It is, therefore, an object of this invention to provide in a container of the type described, means for collapsing the erected container for shipping and storage purposes.

An important object is to provide a container that is fully collapsible and wherein each pair of panels con-

2

nected by a diagonal score line will lie in contacting flatwise relation to each other when the container is fully collapsed causing minimum stress and deleterious effect on the box forming materials.

Another important object is to provide an economical collapsible container which may be assembled from a one piece blank and having sealed bottom closure flaps and foldable top closure flaps.

Another object is the provision in a regular slotted 10 carton means for collapsing the erected container by the manufacturer which will in turn permit the collapsed container to be re-erected by the user into a box-like condition without the aid of any additional equipment or materials.

A further object is to provide a container with scores 15 diagonally arranged, in the side vertical walls and in the top flaps which are hingedly connected to the side vertical walls, in such a manner that said diagonal scores will permit collapsing the erected and bottom sealed container.

A still further object is to provide a container that may be collapsed following initial usage for purposes of economical storage or transportation and then again erected for further utilization.

Another object is to provide a collapsible container 20 that is free standing and rigid in the fully erected or re-erected form before placing the contents therein.

Other objects and advantages of this invention will be apparent to those skilled in the art upon a full and complete understanding of the construction of the container. 25 The accompanying drawings illustrate an embodiment of the invention and form a part of the specification. Like numerals and symbols therein appearing refer to like parts wherever they occur.

Fig. 1 is a plan view illustrating the container embodying a preferred form of the invention;

Fig. 2 is a perspective view of the completely erected container as formed by the manufacturer from the blank shown in Fig. 1;

Fig. 3 is a perspective view of a container as shown 30 in Fig. 2 in a partially collapsed condition;

Fig. 4 is a perspective view of a further stage of collapsing the container;

Fig. 5 is a view of a container, as illustrated in Fig. 2, 35 in a fully collapsed condition; and

Fig. 6 is a perspective view of a re-erected container with the side top flaps turned outwardly in a substantially right angular relationship to the side panels, thereby providing a rigid condition to the container walls to facilitate convenient and accurate placement of the articles 40 to be packed in the container.

The blank for the collapsible container, illustrated in Fig. 1, comprises vertical side wall panels 10 and vertical end wall panels 11 hingedly connected in side by 45 side relation and defined by horizontal flap scores 12 and 13 and vertical corner scores 14. The top, side closure flaps 15 are hingedly connected to the upper edges of side panels 10 by flap score 12 and are separated by slots 16. The top, end closure flaps 17 are 50 hingedly connected to the upper edge of vertical end walls 11 by flap scores 12 and are separated by slots 16. Bottom closure flaps 18 are hingedly connected to the lower edges of the vertical wall panels 10 and 11 by flap score 13.

The blank illustrated in Fig. 1 may be erected by the manufacturer in any convenient manner. In a preferred method the side and end walls may be folded inwardly about vertical scores 14 into a tubular relation and assembly flap 19 brought into parallel contacting relation 55 with the then adjacent vertical end wall 11 and secured thereto by staples or adhesively bonding in a manner well known. Assembly flap 19 may be omitted and the

abutting free edges of outer panel 10 and outer panel 11 hingedly connected by means of tape in a manner well known. The bottom flaps 18 are then folded about flap score 13 inwardly in a right angular overlapping relationship and secured thus by staples, adhesively bonding, or tape. The completion of this operation by the container manufacturer effects the fully erected container illustrated in Fig. 2.

The diagonal scores 20 positioned in vertical side panels 10 substantially bisect the angles included between the vertical corner scores 14 and horizontal flaps score 13 and converge upwardly and inwardly, in respect to each other, until terminated at flaps score 12. The diagonal scores 21 positioned in the top side closure flaps 15, initiate at the convergent termination of diagonal score 20 and diverge upwardly and outwardly to the free edges of the top closure flaps in a right angular relation to the diagonal scores 20.

In order to collapse the container as illustrated in Fig. 2, the end panels 11 and attached end closure flaps 17 are folded inwardly and downwardly about flap score 13 in the manner illustrated successively in Figs. 3 and 4 to a flatwise relation essentially parallel to the plane formed by the sealed bottom closure flaps 18. Simultaneously the portions of side panels 10 defined by flap score 13, the converging diagonal scores 20, and the point on flap score 12 or the intersecting section of flap score 12, said point or section of flap score 12 being identified as 22, are forced outwardly and downwardly about flap score 13 to a flatwise relation. At the same time the portions of top side wall flaps 15, determined by the diverging diagonal scores 21 and the point on flap score 12 or the intersecting section of flap score 12, identified as 22, fold inwardly and thereby trap therebetween the fan folded remaining portions of vertical side panels 10 and top side panels 15. Thus the portions of the side walls and their top flaps connected at least in part by said diagonal scores will be in flatwise contacting relation to each other without intervening plies of paperboard at the scores providing complete collapsing without crushing stresses on the folds. The resulting fully collapsed container is in condition for economical storage shipping and handling as illustrated in Fig. 5.

Re-erection of the collapsed container by the user may be performed by grasping the free margin edges of the infolded top side flaps 15 and lifting said flaps and thereby simultaneously causing the side wall panels 10 and end wall panels 11 to attain the fully erected condition illustrated in Fig. 2. Further, in one continuing motion the top side flaps 15 may be folded outwardly to a right angular relationship to the vertical side walls 10, as illustrated in Fig. 6, and thereby cause complete rigidity of the side walls to facilitate accurate placement of desired contents in the container.

Upon loading the container, final closure of the top flaps 13 and 17 is accomplished by stitching, taping, or adhesively bonding in a manner well known.

It is to be understood that the embodiments herein described are illustrative and not restrictive, and it is also to be understood that the invention may be susceptible of embodiment in other modified forms, and that

all such modifications which are similar to or equivalent hereto come equally within the scope of the claim next appearing.

I claim:

5 A container fully collapsed in flatwise relationship for shipping, the container having opposed pairs of connected side and end wall panels to which are foldably connected by means of scores top and bottom closure flaps, the bottom closure flaps being infolded and secured in overlapping relationship, the side walls each being diagonally scored and with the scores extending in converging relationship and with each score on each side wall extending from respective corners of the side wall panels to the flap score of each side wall panel, the scores on 10 each side wall panel terminating in spaced relationship with each other at the flap score and thus defining a mid section and a substantially triangular section extending from each side thereof, the top flap of each side wall being diagonally scored and with the scores converging 15 from the free edges thereof inwardly from end edges toward and terminating adjacent the terminus of the converged ends of the scores on each side wall and thus forming a mid section with modified triangular sections extending from each side thereof, the score line of each 20 side panel defining adjacent portions of the mid sections and the triangularly shaped sections on the side walls and the modified triangular sections on each closure flap, the end wall panels with their respective closure flaps extended outwardly thereof being infolded in overlapping 25 substantially flatwise condition and over the infolded bottom closure flaps, the mid section of each side wall being folded outwardly beyond the infolded bottom flaps, each triangular section of each side wall being infolded and overlapping an adjacent portion of the mid section of 30 each side wall, each modified triangular section of the closure flap being outwardly folded from each infolded triangular side wall section and overlapping a portion of each adjacent triangular section of the side wall, the mid portion of each closure flap being infolded and having 35 end portions thereof overlapping portions only of the outwardly folded modified triangular sections of the closure flap, and with a central portion of the infolded mid section of the closure flap being overlapped relationship with an adjacent exposed inner portion of the mid 40 section of the side wall, whereby when the infolded mid sections of the side wall closure flaps are grasped and raised and moved inwardly toward one another, the side walls including the triangular sections thereof will be moved to erected condition simultaneously with the end 45 walls to form a container.
